(57) **CLAIM**

The ornamental design for a frog toy, as shown.

DESCRIPTION

FIG. 1 is an oblique view of a frog toy according to the present application.

FIG. 2 is a top view of the frog toy of FIG. 1.

FIG. 3 is a bottom view of the frog toy of FIG. 1.

FIG. 4 is a front view of the frog toy of FIG. 1.

FIG. 5 is a back view of the frog toy of FIG. 1.

FIG. 6 is a left view of the frog toy of FIG. 1; and,
FIG. 7 is a right view of the frog toy of FIG. 1.

The broken lines are included for the purpose of illustrating environmental structure and form no part of the claimed design.
